A. E. LUNDELL

TELEPHONE EXCHANGE SYSTEM

Filed Nov. 6, 1920

Inventor:
Alben E. Lundell.
By *S. C. Hansen*, Atty.

UNITED STATES PATENT OFFICE.

ALBEN E. LUNDELL, OF NEW YORK, N. Y., ASSIGNOR TO WESTERN ELECTRIC COMPANY, INCORPORATED, A CORPORATION OF NEW YORK.

TELEPHONE-EXCHANGE SYSTEM.

Application filed November 6, 1920. Serial No. 422,256.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems, and more particularly to systems in which a manual operator establishes connections to subscribers' lines and P. B. X. trunks by means of a plug ended cord circuit.

It is the object of this invention to provide a system and apparatus such that accurate connections may be obtained quickly and as a result of a minimum number of manual operations by an operator.

More specifically, the invention is directed to a system in which an operator serves groups of P. B. X. trunks in addition to subscribers' lines, and is of special utility when it happens that the P. B. X. trunks are arranged in groups of large capacity.

When there are a large number of trunks in any given group the usual method of establishing connection requires that the operator test these trunks successively. Regardless of the efficiency of the operator a considerable time interval is required in a case of a trunk group of for example, 100 to 500 trunks, and there is in addition the danger that in testing these trunks at a high rate of speed the operator may plug in without fully receiving or noticing the busy tone.

It is a further object of the invention to provide automatically operated mechanism associated with an operator's position such that when she inserts the calling plug into a jack associated with the group of trunks to which the connection is to be extended, an idle trunk will automatically be selected and the incoming end of the link circuit will be automatically extended to such trunk, and signaling current will be applied to such selector trunk without further attention by the operator.

It is an additional object of the invention to provide automatic switching means which

will automatically operate to select the desired group of trunks when the operator plugs into the jack associated with such group.

A feature of the invention is the provision of controlling means in connection with the jack associated with a group of trunks, to control the operation of the automatic switching device.

A further feature of the invention is the use of a universal cord circuit, that is, a cord circuit which will function correctly either with an ordinary subscriber's line, or with a P. B. X. trunk by means of the special automatic switching equipment.

It is thought that the invention will best be understood from the following detailed description, reference being had to the accompanying drawing.

In the drawing the figure shows so much of a telephone system as is necessary to an understanding of the invention.

The automatic switch, the circuits of which are shown in the lower left-hand portion of the drawing, is similar in mechanical construction and method of operation to that shown in Patent No. 1,308,867, issued July 8, 1919, to J. N. Reynolds. This switch has been used in order to simplify the disclosure as much as possible. It is a 500 point switch arranged to have five multiple brushes, each of which has access to ten groups of ten lines each. It will, therefore, be assumed that the operator whose cord circuit is indicated at O' has access to fifty groups of P. B. X. trunks, there being ten trunks in each group. In practice it is desirable to use the system in connection with trunk groups of larger capacity. In this case, selection of a group of trunks may be made by means of an ordinary two-motion step-by-step switch, and an idle trunk may then be selected by means of a series (there being any desired number of switches in the series) of small step-by-step switches which would be successively operated to find an idle trunk. The invention is, therefore, not to be limited to the specific embodiment shown, since this is, as pointed out above, merely a simplified disclosure.

100

The operation of the system in case the subscriber at substation A desires to extend the call to the substation at B, will first be described.

- 5 When the subscriber at A removes his receiver from the switchhook, line relay 1 is energized by means of a circuit extending from grounded battery, winding or relay 1, inner armature and back contact of cut-off relay 2 to ground. The energization of relay 1 causes the illumination of lamp 3.
- 10 relay 2, over the loop of the calling subscriber's line, including the substation apparatus, outer armature and back contact of relay 2 to ground. The energization of relay 1 causes the illumination of lamp 3.
- 15 The operator whose cord circuit is indicated at O upon observing the lighting of lamp 3, inserts answering plug 4 into jack 5 associated with lamp 3. A circuit is then completed from grounded battery, resistance 6, sleeve contacts of plug 4 and jack 5, winding of cut-off relay 2 to ground. Relay 2 is energized in this circuit and attracts its armatures, thus causing the de-energization of relay 1, which in turn causes lamp 3 to be extinguished. The "A" operator at O, by means of a listening key (not shown) may then connect her head set (not shown) to the cord circuit and converse with the calling subscriber to ascertain the number of the wanted line. The operator at O upon learning that the call is to be extended to a subscriber in a distant office then converses with the operator at such distant office by means of an order wire. The operator at the distant office receives the number of the wanted line and assigns a trunk circuit for the use of the operator at O. The "A" operator then inserts calling plug 7 into trunk jack 8, whereupon a circuit is completed from grounded battery, lower right-hand winding of repeating coil 9, winding of supervisory relay 10, ring contacts of plug 7 and jack 8, lower left-hand winding of the repeating coil 11, left-hand winding of relay 12, upper left-hand winding of repeating coil 11, tip contacts of jack 8 and plug 7, upper right-hand winding of repeating coil 9 to ground. Relay 12 is energized in this circuit and completes a circuit from grounded battery, lamp 13, middle lower armature of relay 14 and its back contact, conductor 15, left-hand armature and back contact of relay 59, armature and front contact of relay 12 to ground. Lamp 13 is lighted to inform the "B" operator at O' that connection has been extended to the trunk circuit.

- 65

When the operator at O' observes the lighting of lamp 13 she inserts plug 16 into multiple jack 17 associated with the desired line. If the wanted line is busy, the operator will receive a click in her headset when the tip of the plug engages the sleeve contact of jack 17, since the busy condition of the line is indicated by the presence of bat-

tery potential supplied to the sleeve contact of jack 17, in a manner to be hereinafter described. Current flowing from the battery to the sleeve contact of jack 17, tip contact of plug 16, upper armature and back contact of relay 14, winding of induction coil 18 to ground induces a current in the circuit of the operator's receiver, causing a click to inform her that line is busy.

Assuming however, that the wanted line is idle, the operator inserts plug 16 completely into jack 17 whereupon a circuit is completed from grounded battery, winding of relay 14, sleeve contacts of plug 16 and jack 17, winding of cut-off relay 19 to ground. Relays 14 and 19 are energized in this circuit while the battery supplied to the sleeve contacts of the other multiple jacks of the wanted line, will render these jacks busy to other testing operators. The energization of cut-off relay 19 removes the control of the called subscriber's line relay in the well-known manner. The energization of relay 14 extends the tip and ring conductors of the cord circuit to the tip and ring contacts of the plug and completes at the same time, a circuit from grounded battery, winding of relay 20, left-hand armature and back contact of relay 21, right-hand armature and back contact of ringing relay 22, lowermost armature and front contact of relay 14, conductor 15, back contact and left-hand armature of relay 59, armature and front contact of relay 12 to ground. The relay 20 is energized in this circuit. It is to be noted that the winding of relay 21 is included in a branch path of the energizing circuit of relay 20, but since it is shunted by a low resistance path, relay 21 does not energize at this time.

It is to be observed that relay 14 upon energization, opens at its middle lower armature, the circuit of the supervisory lamp 13, thus allowing this lamp to be extinguished.

The energization of relay 20 completes the ringing circuit which extends from ground through a source of alternating ringing current 23, winding of relay 22, lower armature and front contact of relay 20, inner lower armature and front contact of relay 14, ring contacts of plug 16 and jack 17, thence through the loop of the called substation line, including the bell magnets and condenser, tip contacts of jack 17 and plug 16, upper armature and front contact of relay 14, upper armature and front contact of relay 20 to ground. The current flowing in the above traced circuit causes the bell at substation B to be rung. When the subscriber at the substation answers and removes his receiver from the switchhook, the resistance of the circuit is decreased sufficiently to allow marginal relay 22 to operate.

105

110

115

120

125

130

The operation of relay 22 removes the shunt from about the winding of relay 21, and this relay is energized and completes a locking circuit for itself from grounded battery by way of its left-hand armature and front contact. The application of battery directly to the winding of relay 21 shunts out the winding of relay 20. Relay 20 is deenergized and connects through the right-hand windings of repeating coil 11 to the tip and ring conductors respectively. Current flow through the substation of the called subscriber causes the energization of supervisory relay 24. The connection is now complete and the subscribers may converse.

When connection is no longer desired both subscribers replace their receivers.

Before continuing the description, it might be well to observe that the supervisory relays 10 and 75 in the cord circuit at O were energized during talking, supervisory relay 75 having been energized over the loop of the calling line. Supervisory relay 10 is marginal in operation, that is, when relay 24 is not energized and the circuit of relay 10 extends through the left-hand high resistance winding of relay 12, relay 10 cannot be energized. However, when the called subscriber answers, a parallel low resistance path is provided through the low resistance right-hand winding of relay 12, and the increased current flow which results allows relay 10 to be energized.

When the called subscriber replaces his receiver, supervisory relay 24 is deenergized, causing in turn the deenergization of marginal relay 10.

When the calling subscriber replaces his receiver, supervisory relay 75 is deenergized. The operator at O upon observing the lighting of the supervisory signals controlled by supervisory relays 75 and 10, respectively, removes plugs 4 and 7 from jacks 5 and 8 respectively. The removal of plug 7 from jack 8, causes the deenergization of relay 12, whereupon a circuit is completed from grounded battery, lamp 13, middle lower armature and front contact of relay 14, armature and back contact of relay 12 to ground. Lamp 13 is now lighted to inform the operator at O' that connection is no longer desired, and she thereupon removes plugs 16 from jack 17. All parts of the apparatus have now been restored to their normal condition.

The operation of the system in case the subscriber at substation A desires to call a P. B. X. station indicated at "C," will now be described. In this case the operation of this system is identical with that previously described up to the point where the operator at O' is ready to extend the call by means of plug 16, it being remembered that she has

received the designation of the wanted line by means of an order wire, and that the lighting of lamp 13 has indicated to her that the call has been extended to her position.

In the present case, since the call is to be directed to a trunk in a P. B. X. group, the operator inserts plug 16 into jack 25, which is the jack individual to the particular group of P. B. X. trunks to which connection is to be extended. A circuit is thereupon completed from grounded high resistance left-hand winding of relay 26, ring conductors of jack 25 and plug 16, inner lower armature and back contact of relay 14, conductor 27, side switch arm 28 and its first contact, winding of marginal relay 29 to grounded battery. Relay 26 is energized in this circuit, but relay 29 being marginal, does not become energized due to the presence of the high resistance left-hand winding of relay 26 in its circuit.

The impulse sending device shown in the lower right-hand portion of the drawing is constantly rotated from any desired source of power in the direction indicated by the arrow, it being understood that the impulse sending device is in the form of a cylinder which has been developed into a plane surface for the sake of disclosure. When brush 31 engages pick-up segment 32, a circuit is completed from grounded battery, segment 32, brush 31, make-before-break contacts of relay 33, winding of relay 33, left-hand armature and front contact of relay 26 to ground. Relay 33 is energized in this circuit and completes a locking circuit for itself extending from grounded battery, inner left-hand armature and front contact of relay 33 to ground, as described.

Immediately upon the energization of relay 33, marginal relay 29 becomes energized, its circuit extending from grounded battery, winding of relay 29, side switch arm 28 and its first contact, conductor 27, inner lower armature and back contact of relay 14, ring contacts of plug 16 and jack 25, right-hand low resistance winding of relay 26, right-hand armature and front contact of relay 26, right-hand armature and front contact of relay 33, right-hand armature and back contact of relay 34, brush 35, which is resting on a conducting portion of drum 36, to ground. The energization of relay 29 causes in turn the energization of slow-to-release relay 30.

As soon as brush 35 engages insulating segment 37, relay 29 is deenergized, whereupon a circuit is completed from grounded battery, winding of primary stepping magnet 38, side switch arm 39 and its first contact, winding of slow-release relay 40, inner right-hand armature and front contact of relay 30, armature and back contact of relay 29 to ground. Primary magnet 38 is energized to rotate the auxiliary shaft one step. Relay 40 is energized and remains en-

ergized during the sending of the first series of impulses. As soon as brush 35 engages a conducting portion of drum 36, relay 29 is again energized, thereby allowing magnet 38 to complete its retractive movement into engagement with another tooth of the ratchet wheel which operates the auxiliary shaft of the switch. In this manner, three impulses will be supplied to cause the switch to advance three steps in a primary or main group selecting movement.

It is to be observed that during the sending of impulses the continued energization of relay 40 maintains the circuit of escape magnet 41 by ways of side switch arm 42 and its first contact, and the front contact and armature of relay 40. As soon as brush 35 leaves insulating segment 43, at which time three impulses will have been transmitted to stepping relay 29, relay 29 will remain energized for a relatively long period, thus allowing relay 40 to be deenergized. Relay 40 upon deenergization, causes the deenergization of escape magnet 41 which releases and advances the side switch into its second position.

When pick-up brush 47 engages conducting segment 48 of drum 49, a circuit is completed from grounded battery, segment 48, brush 47, make-before-break contact of relay 34, winding of relay 34, left-hand armature and front contact of relay 33 to ground. Relay 34 is energized in this circuit and locks up by way of its left-hand armature and front contact. The energization of relay 34 extends the impulse conductor to brush 50, it being assumed that connection to a trunk in the ninth sub-group in the main group served by the third brush is desired.

The multiple connections on the leads extending from the various brushes of the impulser drum indicate how the impulser is connected to the relays associated with other jacks corresponding to jack 25. There is associated with each jack corresponding to jack 25 a set of relays corresponding in every way to relays 26, 33 and 34. Brushes 31 and 47 are multiplied to contacts of other relays 33 and 34, in a manner identical with that shown for the particular relays which have been disclosed. The various brushes which determine the number of impulses to be sent are connected to the front and back contacts of the right-hand armatures of relays corresponding to relay 34 in such a manner that any combination of impulses required to select the particular group of trunks desired may be obtained.

As soon as brush 50 engages insulating segment 46 of drum 36, current flowing through relay 29 is decreased to a sufficient extent to cause the deenergization of this relay. Since the side switch associated with the selector is in its second position, a circuit is thereupon completed from grounded

battery, winding of stepping magnet 44, side switch arm 39 and its second contact, winding of slow-release relay 40, inner right-hand armature and front contact of relay 30, armature and back contact of relay 29 to ground. Stepping magnet 44 and slow-release relay 40 are energized in this circuit, relay 40 causing in turn the energization of escape magnet 41. As brush 50 passes over the succeeding insulating segments, relay 29 is intermittently deenergized and energized to cause the advance of the brush shaft in a sub-group selecting movement under the control of magnet 44. As before, relay 40 remains energized during the sending of the series of impulses. When brush 50 leaves insulating segment 51, at which time nine impulses will have been sent, relay 29 remains energized for a relatively long period of time causing the deenergization of slow-release relay 40, which in turn allows escape magnet 41 to deenergize to advance the side switch into its third position.

As soon as the side switch reaches its third position, a circuit is completed from grounded battery, winding of test relay 52, make-before-break contact of such relay, side switch arm 53, and its third contact, right-hand armature and front contact of relay 29 to ground. Relay 52 is energized and locks up by way of its left-hand armature, side switch armature 54 and its third contact to ground by way of off-normal contact 55, which does not open until the selected brush set has made its first step outwardly. It is to be noted that as the impulser continues to rotate, brush 50 will cause intermittent deenergizations of relay 29 as it engages the primary set of segments served by it. These momentary interruptions can have no ill effect at this time, however, since slow-release relay 40 is maintained energized to prevent the release of the side switch and since no impulses can be transmitted due to the fact that side switch arm 39 has been advanced to its third position.

The energization of test relay 52 completes a circuit for side switch magnet 41, extending from grounded battery winding of magnet 41, inner right-hand armature and front contact of relay 52 to ground. At the same time, a circuit is completed from grounded battery, winding of magnet 44, armature and back contact of magnet 44, outer right-hand armature and front contact of relay 52 to ground. Relay 44 is energized and causes the selected brush set to be moved into engagement with the terminals of the first idle trunk in the selected sub-group. Assuming that this trunk is busy and that busy trunks are characterized by the presence of ground potential on their test terminals, relay 52 will be maintained ener-

gized irrespective of the opening of off-normal contact 55, since holding ground is now applied to test brush 56 by way of the busy test terminal. Relay 52 remains energized 5 until an ungrounded test terminal is encountered, the brush set being meanwhile moved inwardly under the control of magnet 44, which interrupts its own circuit to cause such advance. When test brush 56 encounters the test terminal of an idle trunk, relay 52 is deenergized, thus opening the stepping circuit of magnet 44 and at the same time allowing magnet 41 to deenergize 10 to move the side switch into position 4.

15 In position 4 of the side switch, a circuit is completed from grounded battery, high resistance winding of relay 57, side switch arm 28 and its fourth contact, conductor 27, inner lower armature and back contact of relay 14, ring conductors of plug 16 and jack 25, left-hand high resistance winding of relay 26 to ground. Relay 57 is energized in this circuit, but the inclusion of its high resistance winding in the circuit of relay 26 20 causes relay 26 to deenergize, thus causing in turn the deenergization of relays 33 and 34.

It is to be observed that when the side switch reaches position 4, a circuit is completed from grounded battery, winding of 30 escape magnet 41, armature and back contact of escape magnet 41, side switch arm 61 and its fourth contact, side switch arm 62 and its fourth contact, armature and back 35 contact of relay 57 to ground. Escape magnet 41 starts to energize, but before its winding can be sufficiently saturated to move its armature and the side switch controlled by its relay 57, which is a quick-acting relay, 40 operates and removes the energizing ground from the winding of magnet 41.

With relay 57 energized, energizing circuits for relays 58 and 59 are completed by way of side switch arm 60, and its fourth 45 contact, and the armature and front contact of relay 57 to ground.

The energization of relay 58 connects through the tip and ring conductors of the trunk, by way of conductors 63 and 64, to 50 brushes 65 and 66 and thence over the selected trunk to the desired P. B. X. The energization of relay 59 opens at its left-hand armature, the circuit of lamp 13 and this lamp is extinguished to inform the operator 55 that connection has been established to the desired P. B. X. The energization of relay 59 also completes a circuit for supplying signalling current to the selected trunk by causing the energization of relay 20. Relay 60 20 is energized over a circuit extending from grounded battery, winding of relay 20, left-hand armature and back contact of relay 21, right-hand armature and back contact of relay 22, outer right-hand armature and 65 front contact of relay 59, armature and

front contact of relay 12 to ground. At the same time, a circuit is in existence for relay 21, but this relay is shunted by the direct path through the armatures and back contacts of relays 21 and 22 respectively. 70

Relay 20 upon energization completes a circuit from ground, through a source of signalling current 23, winding of relay 22, lower armature and front contact of relay 20, conductor 63, inner armature and front contact of relay 58, brush 66, terminal 67 and thence over the trunk conductor, through the signalling apparatus at P. B. X., C, terminal 68, brush 65, outer armature and front contact of relay 58, conductor 64, upper armature and front contact of relay 20 to ground. When the P. B. X. attendant at C answers the call, the resistance of the line circuit is lowered enough to allow marginal relay 22 to be energized. Marginal 80 relay 22 upon energization removes the shunt from about the winding of relay 21, and relay 21 is energized and completes a locking circuit for itself, which in turn shunts down relay 20 as previously described. Relay 20 upon deenergization connects the tip and ring conductors from the repeating coil to conductors 63 and 64. Connection to the wanted P. B. X. has now been established, it being observed that supervisory relay 24 is energized to include the low resistance right-hand winding of relay 12 and thus allow supervisory relay 10 to 85 operate. 90

The P. B. X. attendant will extend the 100 call to the desired station in the P. B. X., and when connection is no longer desired, the calling subscriber will replace his receiver thus causing the deenergization of relay 75 to allow the operation of the calling supervisory signal at the O position.

When the P. B. X. attendant disconnects 105 from the trunk, supervisory relay 24 will be deenergized, thus causing in turn the deenergization of supervisory relay 10. When the operator at O notes that both supervisory 110 signals are lighted, she removes plugs 4 and 7 from jacks 5 and 8 respectively.

Removal of plug 7 from jack 8 causes the 115 deenergization of relay 12, whereupon a circuit is completed from grounded battery, lamp 13, conductor 69, inner right-hand armature and front contact of relay 59, armature and back contact of relay 12 to ground. The resultant lighting of lamp 13 120 informs the operator at O' that connection is no longer desired and she thereupon removes plug 16 from jack 25, thus allowing relay 57 to be deenergized. As soon as relay 57 is deenergized a circuit is completed from grounded battery, winding of side switch magnet 41, armature ad back contact of magnet 41, side switch arm 61 and its fourth contact, side switch arm 62 and its fourth 125 contact, armature and back contact of relay 130

57 to ground. Escape magnet 41 is energized and interrupts its own circuit to advance the side switch into the fifth position. Magnet 41 continues to advance the side switch in a self-interrupting circuit until the side switch reaches position 8. The side switch in rotating controls cam discs as described in the above mentioned Patent No. 1,308,867 and when these cam discs reach their 10 seventh position the release and restoration of the shafts and brushes takes place. When the shafts are fully restored, normally closed contact 70 closes and a circuit is completed from grounded battery, winding of magnet 41, armature and back contact of magnet 41, contact 70, closed when the switch is in its normal position, side switch arm 61 and its eighth contact, side switch arm 62 and its eighth contact, armature and back 15 contact of relay 57 to ground. Magnet 41 20 interrupts its own circuit and advances the side switch into position 1.

Since relay 21 was deenergized upon the deenergization of relay 12 and since relays 25 58 and 59 were deenergized upon the deenergization of relay 57, it is apparent that all parts of the apparatus have now been restored to their normal position.

As described, the invention has been 30 shown in connection with a switch arranged to serve 50 groups of trunks. It is obviously within the ability of one skilled in the art to arrange the system to provide for a much larger group of trunks by arranging 35 the impulsor to transmit any desired number of impulses. The manner in which the impulse conductor is extended to the various brushes in case a different group of trunks is desired may be readily understood without further description.

If, for any reason, the operator at O' should remove the plug 16 from jack 25 before the switch has fully completed its operation, the restoration of the switch will 45 be accomplished as follows:

When plug 16 is removed from jack 25, relay 29 is deenergized causing in turn the deenergization of slow-release relay 30. Provided that no impulses have been sent, 50 relay 40 will be energized before slow-release 30 is deenergized and magnet 38 will cause the auxiliary shaft to be rotated one step. Since no impulses are sent, relay 40 deenergizes and causes the side switch to advance 55 into its second position. An obviously traceable self-interrupting circuit is then completed for escape magnet 41 which causes the side switch to be advanced into position 3. From position 3 of the side switch, the 60 side switch and switch proper are restored to their normal position as previously described.

What is claimed is:

1. In a telephone exchange system, an 65 operator's position, groups of outgoing

trunk lines, an incoming line terminating in a connecting plug, a jack individual to each group of outgoing lines, an automatic switch associated with said incoming line, and means operative upon the insertion of said plug into a desired one of said jacks to operate 70 said automatic switch to select the group of trunks to which said jack is individual.

2. In a telephone exchange system, an 75 operator's position, groups of outgoing trunk lines, an incoming line terminating in a connecting plug, a jack individual to each group of outgoing lines, an automatic switch associated with said incoming line, means 80 operative upon the insertion of said plug into a desired one of said jacks to operate said automatic switch to select the group of trunks to which said jack is individual, and means to select an idle trunk in the selected group.

3. In a telephone exchange system, an operator's position, groups of outgoing trunk lines, an incoming line terminating in a connecting plug, a jack individual to each group 90 of outgoing lines, an automatic switch associated with said incoming line, means operative upon the insertion of said plug into a desired one of said jacks to operate said automatic switch to select the group of trunks to which said jack is individual, and means to extend a connection from said incoming line to said selected idle trunk.

4. In a telephone exchange system, an operator's position, an incoming line terminating in a connecting plug, an automatic switch associated with said incoming line, a signal and a source of signalling current associated with said incoming line, groups of outgoing trunk lines, a jack individual 100 to each group of outgoing trunk lines, a plurality of outgoing subscribers' lines, a jack individual to each of said lines and appearing at said operator's position, means operative upon the insertion of said connecting plug into the jack of a subscriber's line to extend connection thereto, means operative upon the insertion of said plug into a desired one of said group jacks to operate said automatic switch to select an idle trunk 105 in the associated group, and means to supply said signalling current to the outgoing lines and to cause the correct operation of said signal in the case of either type of connection.

5. In a telephone exchange system, an operator's position, groups of outgoing trunk lines, an incoming line terminating in a connecting plug, a jack individual to each group of outgoing lines, a step-by-step automatic switch associated with said incoming line, and means associated with said jacks to supply a desired number of impulses to said automatic switch when said plug is inserted into a desired one of said jacks, to 125

cause said automatic switch to select the group of trunks to which said jack is individual.

6. In a telephone exchange system, an operator's position, groups of outgoing trunk lines, an incoming line terminating in a connecting plug, a jack individual to each group of outgoing lines, a step-by-step automatic switch associated with said incoming line, an impulse generating device common to said groups of trunk lines, and means operative upon the insertion of said plug into a desired one of said jacks to operate said automatic switch by means of impulses supplied from said impulse generating device, to cause said automatic switch to select the group of trunks to which said jack is individual.

7. In a telephone exchange system, an operator's position, groups of outgoing trunk lines, an incoming line terminating in a connecting plug, a jack individual to each group of outgoing lines, a step-by-step automatic switch associated with said incoming line, means associated with said jacks to supply a desired number of impulses to said automatic switch when said plug is inserted into a desired one of said jacks to cause said automatic switch to select the group of trunks to which said jack is individual, and means to select an idle trunk in the selected group.

8. In a telephone exchange system, an operator's position, groups of outgoing trunk lines, an incoming line terminating in a connecting plug, a jack individual to each group of outgoing lines, a step-by-step automatic switch associated with said incoming line, an impulse generating device common to said groups of trunk lines, and means operative upon the insertion of said plug into a desired one of said jacks to operate said automatic switch by means of impulses supplied from said impulse generating device to cause said automatic switch to select the group of trunks to which said jack is individual.

9. In a telephone exchange system, an operator's position, outgoing trunk lines arranged in groups and sub-groups, an incoming line terminating in a connecting plug, a jack individual to each sub-group of outgoing lines, an automatic switch associ-

ated with said incoming line, and means operative upon the insertion of said plug into a desired one of said jacks to operate said automatic switch to select the sub-group of trunks to which said jack is individual.

10. In a telephone exchange system, an operator's position, outgoing trunk lines arranged in groups and sub-groups, an incoming line terminating in a connecting plug, a jack individual to each sub-group of outgoing lines, an automatic switch arranged for two directive movements associated with said incoming line, and means operative upon the insertion of said plug into a desired one of said jacks to operate said automatic switch in two directive movements to select the sub-group of trunks to which said jack is individual.

11. In a telephone exchange system, an operator's position, outgoing trunk lines arranged in groups and sub-groups, an incoming line terminating in a connecting plug, a jack individual to each sub-group of outgoing lines, a step-by-step automatic switch arranged for two directive movements associated with said incoming line, and means associated with said jacks to supply two series of impulses to operate said automatic switch in two directive movements when said plug is inserted into a desired one of said jacks to cause said automatic switch to select the sub-group of trunks to which said jack is individual.

12. In a telephone exchange system, an operator's position, outgoing trunk lines arranged in groups and sub-groups, an incoming line terminating in a connecting plug, a jack individual to each sub-group of outgoing lines, a step-by-step automatic switch arranged for two directive movements associated with said incoming line, an impulse generating device common to said trunk lines, and means operative upon the insertion of said plug into a desired one of said jacks to operate said automatic switch in two directive movements by means of two series of impulses supplied from said impulse generating device to cause said automatic switch to select the sub-group of trunks to which said jack is individual.

In witness whereof, I hereunto subscribe my name this 30 day of Oct. A. D., 1920.

ALBEN E. LUNDELL.
